UNITED STATES PATENT OFFICE.

JULIUS EDWARD HEILNER, OF NEW YORK, N. Y.

CORSET.

1,293,427.

Specification of Letters Patent.

Patented Feb. 4, 1919.

Application filed June 3, 1918. Serial No. 237,936.

To all whom it may concern:

Be it known that I, JULIUS E. HEILNER, a citizen of the United States, residing at New York, in the county of New York and 5 State of New York, have invented certain new and useful Improvements in Corsets; and I do declare the following to be a full, clear, and exact description of the invention, such as will enable others skilled in the 10 art to which it appertains to make and use the same.

This invention relates to corsets, and it relates more particularly to an improved flesh-reducing corset.

15 The main object of this invention is to provide a corset that effectually reduces the flesh on the back and shoulders of the wearer.

Another object is to provide a corset of 20 this character that allows a sufficient expansion and contraction of the back and shoulders so as to comfortably conform to these portions of the wearer at all times.

Other objects and advantages may 25 come apparent to persons who read the following details of description in connection with the accompanying drawings, in which:

Figure 1 is a perspective view illustrating the front and side portion of my improved 30 corset in use;

Fig. 2 is a similar view illustrating the back and side portion of this flesh reducing corset; and—

Fig. 3 is an enlarged view of the corset 35 out of use and spread substantially in a common plane.

Referring to these drawings in detail, in which similar reference characters correspond with similar parts throughout the several views, the corset consists of two complementary sections 4, which are secured together by the usual lacings 5 through the back stays, and are fastened at the front by means of the usual fastenings 6. These complementary sections being of counterpart construction, the description of one section will suffice for both.

Each corset section 4 comprises a non-elastic waist-engaging portion 7 and an elastic section 8 which extends from the rear lacing strip or back stay horizontally the greater portion of the distance from the back stay to the front stay, so as to extend under the arm of the wearer. Each elastic 55 sheet element 8 also extends above and below the top edge of the front and middle

portions of the corset section, so that the fleshy portions of the back and side above and below the shoulder blade of the wearer are continuously and forcibly, (and yet 60 yieldingly) compressed when this corset is in use. The lower portion of the elastic sheet 8 joins with the upper portion of the non-elastic part 7 and is stitched thereto at 9, the stitching or joint of these two sections extending substantially in a horizontal and rectilinear direction, a plurality of stays 10 cross the joint or seam 9 substantially at right angles and are secured to the elastic and non-elastic portions above and below 65 this seam, the top ends of the stays 10 terminate substantially at the top edge of the elastic portion 8. It will be seen, therefore, that a relatively large portion of the shoulders, sides and back of the wearer are 70 engaged and effectively compressed by means of these elastic sheets which are constructed to have an unusual amount of compressive force, as compared with elastic gores and strips which are sometimes employed in the construction of corsets merely 75 to allow freedom of movement. Such unusual compressive strength of these elements results in applying a sufficient amount of pressure to reduce the flesh on the back and 80 shoulders of the wearer while permitting free muscular movement of the back and shoulders without detriment to the corset or 85 discomfort to the wearer.

Although I have described this embodiment of my invention very specifically, it is to be understood that the relative size of the elastic sheets may be slightly changed without departing from the inventive idea disclosed in the foregoing description and 90 following claims.

What I claim as my invention is:

1. A corset consisting of a pair of complementary sections each comprising a waist-engaging portion which is non-elastic 100 throughout its circumference, a non-elastic bust engaging portion, a non-elastic back stay, and a substantially equilateral elastic shoulder-engaging portion, the bust-engaging portion of each section being located 105 to fit against the part of a person's body forward of the arm pits, the back stay of each section being located to fit against the middle part of the person's back and extending above the level of the arm-pits, the elastic 110 shoulder-engaging portion of each section extending horizontally from one edge of the

2
back stay to the rear edge of the bust-engaging portion of its section and being secured to these edges, the lower edge of each shoulder-engaging portion being secured to the upper edge of the non-elastic waist-engaging portion, the top part of each elastic shoulder-engaging portion terminating at the upper end of the corresponding back-stay, whereby the shoulder-engaging portion overlies and compresses the fleshy portions that cover the shoulder blade of a person wearing the corset.

2. A corset consisting of a pair of complementary sections each comprising a non-elastic waist-engaging portion and an elastic shoulder engaging portion, said elastic

shoulder-engaging portion consisting of an elastic sheet that extends horizontally approximately half the distance across the upper part of the corset section and also extends above and below the top edge of the middle part of this section, each said corset section being provided with a plurality of stays that extend down thereacross substantially from the top of the elastic sheet and across the connection thereof with the non-elastic portion and are secured to the elastic and non-elastic portions. 20 25

In testimony whereof I have hereunto set my hand.

JULIUS EDWARD HEILNER.
